UNITED STATES PATENT OFFICE

154,189

DESIGN FOR A PLANE

Edwin G. Simon, San Francisco, Calif.

Application November 10, 1948, Serial No. 149,550

Term of patent 14 years

(Cl. D93—4)

To all whom it may concern:

Be it known that I, Edwin G. Simon, a citizen of the United States and a resident of the city and county of San Francisco, State of California, have invented a new, original, and ornamental Design for a Plane, of which the following is a specification, reference being had to the accompanying drawing, forming part thereof.

Figure 1 is a perspective view of a plane, showing my new design.

Figure 2 is a side elevation of the plane illustrated in Figure 1.

Figure 3 is a rear elevation of the plane illustrated in Figure 1.

I claim:

The ornamental design for a plane, substantially as shown.

EDWIN G. SIMON.
